(57) **CLAIM**

The ornamental design for a clamping fixture, as shown and described.

DESCRIPTION

FIG. 1 is a top plan view of a bottom portion of the clamping fixture.

FIG. 2 is a side elevational view of the clamping fixture shown in FIG. 1.

FIG. 3 is a top perspective view of the bottom portion of the clamping fixture shown in FIG. 1.

FIG. 4 is a top plan view of a top portion of the clamping fixture.

FIG. 5 is a side elevational view of the top portion.

FIG. 6 is a top perspective view of the top portion of the clamping fixture.

FIG. 7 is a top elevational view of an alternate embodiment of a bottom portion of the clamping fixture.

FIG. 8 is a side elevational view of the clamping fixture shown in FIG. 7.

FIG. 9 is a top perspective view of the bottom portion of the clamping fixture shown in FIG. 7.

FIG. 10 is a top elevational view of a top portion of the alternate embodiment of the clamping fixture shown in FIG. 7.

FIG. 11 is a side plan view of the clamping fixture shown in FIG. 10.

FIG. 12 is a top perspective view of the top portion of the clamping fixture shown in FIG. 10.

FIG. 13 is a top perspective view of the assembled first embodiment of the clamping fixture shown in FIGS. 1 through 6 above.

FIG. 14 is a bottom perspective view of the first embodiment of the clamping fixture shown in FIG. 13.

FIG. 15 is the top perspective view of the assembled second embodiment of the clamping fixture shown in FIGS. 7 through 12; and,

FIG. 16 is a bottom perspective view of the clamping fixture shown in FIG. 15.
